UNITED STATES PATENT OFFICE.

LORENZO D. MOTT, OF MARSHALLTOWN, IOWA.

COMPOUND FOR PRESERVING WOOD AND METAL.

SPECIFICATION forming part of Letters Patent No. 251,918, dated January 3, 1882.

Application filed October 17, 1881. (No specimens.)

To all whom it may concern:

Be it known that I, LORENZO D. MOTT, a citizen of the United States, residing at Marshalltown, in the county of Marshall and State 5 of Iowa, have invented a new and useful composition of matter to be used for the preservation of wood and metal from the action of fire, water, and deleterious gases by rendering the same water-proof, the following being a specification thereof.

My composition consists of the following ingredients, combined in the proportions stated, to wit: gas-tar, thirty-one (31) gallons; sulphur, ten (10) pounds; salt, ten (10) pounds; yellow 15 ochre, ten (10) pounds; brown mineral paint, ten (10) pounds. The gas-tar to be heated, the

other ingredients added, the whole to be thoroughly mixed.

In using the above composition the same should be thoroughly heated and applied hot 20 with a brush to a dry surface.

What I claim, and desire to secure by Letters Patent of the United States, is—

The above-described composition of matter to be used for rendering wood and metal fire 25 and water proof, consisting of gas-tar, sulphur, salt, yellow ochre, and brown mineral paint in about the proportions specified.

LORENZO D. MOTT.
